UNITED STATES PATENT OFFICE.

JOHN L. KNIGHT, OF NEW ALEXANDER, OHIO.

SHIRT.

SPECIFICATION forming part of Letters Patent No. 530,594, dated December 11, 1894.

Application filed March 27, 1894. Serial No. 505,313. (No specimens.)

To all whom it may concern:

Be it known that I, JOHN L. KNIGHT, a citizen of the United States, residing at New Alexander, in the county of Columbiana and State of Ohio, have invented a new and useful

5 Shirt, of which the following is a specification.

The object of this invention is to provide a shirt having starched portions which will not be affected by the perspiration of the 10 wearer; and this end I attain by a peculiar arrangement of a sheet of material, impervious to the perspiration, between the starched portions and the wearer, whereby the perspiration is prevented from going beyond the said 15 sheet and permeating the starched portions. In this peculiar arrangement of the said sheet lies my invention, and I will now describe it in detail and finally embody it in the claim.

In the accompanying drawings: Figure 1 20 represents a sectional view of a shirt-bosom having my improvements applied. Fig. 2 is a cross-section of the same. Fig. 3 is a view of the protecting sheet, showing it detached from the remainder of the shirt. Fig. 4 is a 25 sectional view showing the arrangement of the neck-band. Fig. 5 is a perspective view showing the arrangement of the parts.

The reference numeral 1 indicates the body 30 of the shirt, and 2 the bosom, both of which 30 may be of any preferred construction, and which bosom is connected to the body of the shirt by means of the auxiliary or reinforce sections 3.

4 indicates the sheet of impervious material 35 which I prefer to interpose between the bosom 2 and body 1, and which is of such a size that it will extend entirely under the bosom and beyond the sides thereof. The edges of the 40 impervious sheet 4 extend well under the sections 3, and are stitched by the lines of stitching 9 to the body of the shirt, the said edges having no connection with the sections 3 at its edges. By this construction the wearer 45 will not rumple the bosom 2 by his movements, but the bosom and the edges of sheet 4 will be allowed independent movement.

The sheet 4 is secured in position and to the body 1 by lines of stitching 5, which extend around the edges of the bosom and pass 50 through the shirt-body and sections 3. Thus the sheet 4 is connected to the bosom 2, so as

to brace it and render it rigid, and in addition to the function of preventing the permeating of the bosom; also, by making the edges of sheet 4 loose from the bosom they 55 will be allowed to move freely without rumpling the bosom. The neck-band 6 may also be protected by arranging a strip 7 of impervious material around its inner side, and next to the wearer, so as to cut off the perspiration 60 and prevent it from finding its way to the band 6.

The strip 7 may be secured by any suitable stitching, and I prefer to turn the edges under and stitch them together by the lines 8. 65

By this construction it will be seen that the perspiration of the wearer is prevented from finding its way to the bosom of the shirt, and thereby taking the stiffening out of it. In addition to this, the bosom is braced, and 70 thus its rigidity is secured.

The material of which the sheet 4 may be composed may be rubber or oilcloth. I regard both as equally well adapted to the purpose, with a probable preference to the rubber 75 cloth.

Having described my invention, what I claim is—

A shirt having a body-portion, a sheet of material impervious to moisture, arranged on 80 the outside thereof and secured thereto at its edges, reinforce sections secured to the body and extending inwardly and over the edges of the impervious material, and a bosom arranged over the impervious sheet and extending 85 to the inner edges of the reinforce sections and secured thereto by lines of stitching, said stitching extending through the bosom, reinforce sections and body, whereby the bosom is braced and kept from the 90 perspiration of the wearer, and whereby the edges of the impervious sheet are allowed free movement with the body of the shirt, substantially as and for the purpose described.

In testimony that I claim the foregoing as 95 my own, I have hereto affixed my signature in the presence of two witnesses.

JOHN L. KNIGHT.
